A. BALLENBERG, DEC'D.

F. BALLENBERG, EXECUTRIX.

BEDSTEAD.

APPLICATION FILED SEPT. 6, 1917.

1,287,824.

Patented Dec. 17, 1918.

UNITED STATES PATENT OFFICE.

ADOLPH BALLENBERG, OF NEW YORK, N. Y.; FANNY BALLENBERG EXECUTRIX OF
SAID ADOLPH BALLENBERG, DECEASED.

BEDSTEAD.

1,287,824.

Specification of Letters Patent. Patented Dec. 17, 1918.

Application filed September 6, 1917. Serial No. 189,915.

To all whom it may concern:

Be it known that I, ADOLPH BALLENBERG, a citizen of the United States, and residing at New York, in the county of New York and State of New York, have invented certain new and useful Improvements in Bedsteads, of which the following is a specification, such as will enable those skilled in the art to which it appertains to make and use

10 the same.

This invention relates to bedsteads and particularly to means for connecting the end and side rails with the corner posts, and the object thereof is to provide a simple and effective construction for this purpose whereby the side rails are detachably and reversibly connected with the corresponding corner posts, and by means of which such operation may be quickly and easily performed

15 without the use of tools or implements of any class, and whereby the end rails are secured to the corresponding corner posts by a simple and effective construction, part of which is also employed in making the connection of the side rails with said posts; a still further object being to provide means whereby the detachable side rails may be locked in operative position in which condition they cannot be detached.

20 Another object of this invention is to provide a construction of the class specified which is particularly designed for use in connection with what are known as metal bedsteads but which may be used in connection with bedsteads formed of any desired material.

The invention is fully disclosed in the following specification, of which the accompanying drawing forms a part, in which the 25 separate parts of my improvement are designated by suitable reference characters in each of the views, and in which;

Figure 1 is a plan view of my improved means for attaching the rails of a bedstead to a corner post, the corner post being shown in transverse section, and being tubular in form;

Fig. 2 a section on the line 2—2 of Fig. 1;

Fig. 3 a section on the line 3—3 of Fig. 2;

50 Fig. 4 a plan view of a blank from which the lock member of my improvement is made, said view being on a reduced scale;

Fig. 5 a similar view of a blank from which the body portion of the rail attaching device is made; and

Fig. 6 a view similar to Fig. 3 but on a reduced scale and showing a modification.

In the drawing forming part of this specification, I have shown at *a* one of the corner posts of a bedstead, which, in the construction shown, is tubular in form and is made of sheet metal and, in the practice of my invention, I provide a reinforcing plate *b* which is arc-shaped in cross section and adapted to be mounted on the inner side of 65 the post *a*, and which is provided at intervals with spaced inwardly directed ears *b*² which are arranged in pairs and which are cut from the material of said plate and bent inwardly as shown at *b*³, and the post *a* is 70 provided with corresponding apertures *a*².

I also provide a rail attaching bracket *c* which is formed from a blank *c*², shown in Fig. 5, comprising a central transverse body portion *c*³ provided at its ends with 75 bolt holes *c*⁴, and provided at one side edge with a foldable extension *c*⁵ having a supplemental side edge folding member *c*⁶ provided with a longitudinal slot *c*⁷, and the body portion *c*³ is also provided at its opposite side edge with a foldable side member *c*⁸ provided at one side edge with a foldable member *c*⁹ having two slots *c*¹⁰ and at the other side edge with a similar foldable side member *c*¹¹, one-half *c*¹² of which is 80 foldable at right angles to the other half and the parts *c*³ and *c*⁸ are both cut centrally as shown at *c*¹³ to form inwardly directed bearings *c*¹⁴ when the blank *c*² is folded to form the rail attaching bracket *c*. 90

In the operation of folding the blank *c*² to form the main part of the rail attaching bracket *c*, the transverse central portion of the blank *c*² forms the back plate *c*¹⁵ of the bracket, while the parts *c*⁸ and *c*⁹ are bent at 95 right angles to the back plate to form one side and the bottom of a housing for the bracket as shown in Fig. 3, while the part *c*⁵ is folded at right angles to the back plate to form the opposite side of said housing and 100 the part *c*⁶ of the part *c*⁵ is folded inwardly to form an inwardly directed flange at the bottom of said side of the housing as is clearly shown in Fig. 3, while the part *c*¹¹ of the part *c*⁸ is folded outwardly as shown in 105 Fig. 3 to form an attachment for the end rail *d* of the bedstead which is riveted or otherwise secured thereto as shown at *d*².

I also provide a cam lock device *e* which forms a part of the attaching bracket *c* and 110

which is formed from a blank e^2 shown in Fig. 4, and which comprises a central body portion e^3 having cam-shaped side folding members e^4 and provided at one end with laterally directed ears e^5 , which are bent inwardly as shown in Fig. 2, and the cam-shaped side folding members e^4 are also bent inwardly as shown in Figs. 2 and 3, and in connecting the cam lock device e with the 10 housing part of the rail attaching bracket, said housing part being open at the top, the ears e^5 of the cam lock device are passed inwardly of the sides of the housing portions near the back plate thereof and are pivoted 15 to said sides as shown at e^6 , and the said cam lock device is adapted to be swung vertically as indicated in Fig. 2, and in the downward movement thereof, the points of the cam lock members e^4 pass downwardly 20 through the slots c^{10} in the part c^9 and through the slots c^7 in the part c^6 , all as clearly shown in Fig. 3, and in this position of the cam lock members e^4 of the lock device e said cam lock members e^4 bear on 25 the inwardly directed bearings c^{14} at the sides of the housing of the attaching bracket c .

The part e^8 of the cam lock device e is beveled out or recessed at the back edge thereof as shown at e^7 to correspond with the shape 30 of the post a in transverse section, and to permit said cam lock device to swing into its highest position, and the edge portion or free edge portion of the part e^3 of the cam lock device is also preferably provided with a recess e^8 to permit of the insertion thereunder 35 of the finger to raise said cam lock device when in its operative position, as shown in Fig. 2, or the insertion of a suitable instrument, if said lock device should become fixed 40 in its operative position from any cause.

In the accompanying drawing I have also shown at f one of the side rails of a bedstead, and said rail is composed of angle-iron, one side portion f^2 of which is provided with a 45 reduced angular extension f^3 , having a supplemental reduced extension f^4 , and the part f^3 is provided with a central longitudinal slot f^5 adapted to receive the bearing members c^{14} at either side of the housing of the 50 rail attaching bracket c . In attaching the bracket c to the post, the inner reinforcing plate b is first placed in position with the nuts g in place between the ears b^2 and bolts g^2 are passed inwardly through the back plate 55 c^{15} of the bracket attachment c and through the apertures a^2 in the post a and through the nuts g , and said bolts are secured home tight and this securely locks the bracket attachment to the post, and in the operation 60 of connecting a side rail with the rail attaching bracket c , the lock device e is raised as indicated in dotted lines in Fig. 2, after which the part f^2 of the rail is inserted into the housing of the bracket c and moved laterally into the position shown in Fig. 3, in 65

which operation the bearing c^{14} of the corresponding side of the housing passes inwardly through the slot f^5 in the part f^3 , as indicated in Fig. 3, after which the lock device e is lowered into its operative position 70 as shown in Fig. 3 and the side rail is securely locked against any movement in the housing of the bracket c .

With the foregoing description it will be seen that the side rail f may be connected 75 with the bracket c in two different positions, or in other words, said rail may be reversed and in one position the part f^2 will form the outer side portion of said rail and will be directed upwardly as shown in Fig. 1, 80 while the part f^6 will form the bottom of said rail, and in the other position of said rail the part f^6 will form a flat top surface therefor, while the part f^2 will form the inner side of said rail, which will be directed 85 downwardly as shown in Figs. 2 and 3. It will be noted that the part f^6 is cut away and this forms the extension or part f^3 , and said parts f^6 abuts against the cam e when in 90 its operative position as shown in Fig. 2.

It will be seen that the novel features of 95 my improvement reside primarily in the means for attaching the side rail or rails to the corner post or posts of the bedstead, and with my improvement this operation may be quickly and easily performed, and the side rail or rails will be locked securely in 100 position against any movement whatever and may be quickly and easily detached whenever necessary or desirable.

The object of passing the side portions e^4 of the lock device e down through the bottom of the housing of the bracket c , as shown in Figs. 2 and 3, is to brace the side portions e^4 of the lock device e and make them rigid 105 and immovable when in operation, but in Fig. 6, I have shown a modification in which the same result is accomplished by making the side portions e^4 of said lock devices shorter and providing one of them with an inwardly directed bottom flange plate e^9 which abuts against the other side member e^4 and which braces said parts and holds them 110 rigid when in use.

Having fully described my invention, what I claim as new and desire to secure by Letters Patent, is:—

1. The herein described means for securing 115 a rail of a bedstead to a corner post thereof, consisting of a bracket attachment comprising a back plate adapted to be secured to the post and provided with a housing adapted to receive a part on the rail, and a lock member pivoted in the top of the housing and having parallel side parts adapted to enter said housing between which side parts and one side of the housing the part on the rail is adapted to be secured.

2. A bracket attachment for securing the 120 rail of a bedstead to a corner post thereof,

said attachment being adapted to be secured to said post and comprising a housing adapted to receive a part of one end of the rail, means for securing said part of the rail 5 to said housing against longitudinal movement in both directions and a U-shaped lock member pivoted to the top of the housing and adapted to swing vertically and provided with side portions between which and 10 one side of the housing said part and the end of the rail is adapted to be confined and locked against transverse movement.

3. A bracket attachment for securing a rail of a bedstead to the corner post thereof, 15 said attachment being adapted to be secured to said post and comprising a housing having parallel side members and open at the top, and a lock member pivoted in the top of the housing and having parallel side members 20 adapted to pass into said housing and between which and the sides of the housing are spaces to receive a part on the end of the rail.

4. A bracket attachment for securing a rail of a bedstead to the corner post thereof, 25 said attachment being adapted to be secured to said post and comprising a housing having parallel side members and open at the top, and a lock member pivoted in the top of 30 the housing and having parallel side members adapted to pass into said housing and between which and the sides of the housing are spaces to receive a part on the end of the rail, the sides of the housing being also provided with inwardly directed bearings which 35 are adapted to pass through an aperture in said part of the rail.

5. A bracket attachment for connecting the rails of a bedstead with a corner post 40 thereof, said attachment being adapted to be secured to said post and comprising a housing provided with means for securing an end rail thereto against lateral movement, said housing being open at the top and being 45 adapted to receive a part on an end of a side rail, and a U-shaped lock member pivoted in the top of the housing and having parallel sides adapted to enter said housing and between either of which parallel sides and one 50 side of the housing the part on the end of the side rail is adapted to be secured.

6. A rail attaching and lock device of the class described, said device being composed of two sheet metal parts, one of said parts 55 comprising a back plate having a channel or U-shaped portion extending at right angles

thereto, the other of said parts being U-shaped in form in cross section and adapted to be pivoted in the channel or U-shaped portion of the other part, the opposite sides of said first-named part being provided with inwardly directed members adapted to bear on the opposite sides of said last named part to form between said parts a space adapted to receive the end portion of 60 a rail.

7. A bracket attachment for securing the rail of a bedstead to a corner post thereof, 65 said attachment being adapted to be secured to said post and comprising a housing having parallel side members, a lock member movably mounted between the side members of said housing and having parallel side members, the outer transverse dimension of the lock member being less than the inner 70 transverse dimension of the housing to form spaces of fixed width between the same at the opposite sides of the lock member, and the end of the rail to be connected with said bracket being provided with a part adapted 75 to be mounted in either one of said spaces and locked against transverse movement therein by said lock member and one of the side members of the housing.

8. A bracket attachment for securing the 80 rail of a bedstead to a corner post thereof, said attachment being adapted to be secured to said post and comprising a housing having parallel side members, a lock member movably mounted between the side members 85 of said housing and having parallel side members, the outer transverse dimension of the lock member being less than the inner transverse dimension of the housing to form a space between the same at the opposite 90 sides of the lock member, and the end of the rail to be connected with said bracket being provided with a part adapted to be mounted in one of said spaces and locked against 95 transverse movement therein by said lock member and one of the side members of the housing, and means for locking said part on the end of the rail against longitudinal movement in said space.

In testimony that I claim the foregoing as 100 my invention I have signed my name, in presence of the subscribing witnesses, this 14th day of September, 1917.

ADOLPH BALLENBERG.
